UNITED STATES PATENT OFFICE.

LELIA MAY FELLOM, OF LOS ANGELES, CALIFORNIA.

DESIGN FOR A DOLL.

52,642.

Specification for Design.

Patented Nov. 12, 1918.

Application filed May 11, 1917. Serial No. 168,052. Term of patent 14 years.

To all whom it may concern:

Be it known that I, LELIA MAY FELLOM, a citizen of the United States, residing at Los Angeles, in the county of Los Angeles and State of California, have invented a new, original, and ornamental Design for Dolls, of which the following is a specification, reference being had to the accompanying drawing, forming part thereof.

Fig. 2 is a rear elevation thereof.

I claim:

The ornamental design for a doll, as shown.

LELIA MAY FELLOM.

Witnesses:

EDMUND A. STRAUSE,
MARGUERITE BATES.
